UNITED STATES PATENT OFFICE.

JOSEPH A. BIRKHOLZ, OF ORANGE, NEW JERSEY.

BUILDING UNIT.

Application filed September 9, 1922. Serial No. 587,059.

This invention relates, generally, to improvements in the construction of building units for use in the general construction of buildings, and similar structures; and, the 5 present invention has reference, more particularly, to a novel building unit made of a plastic material, which is molded in the form of a slab, board, or the like, and furthermore, to a novel means of connecting 10 or uniting a number of the units when set up to provide a wall; also to provide a novel means of closing the joints between two of such slabs or boards by means of a batten; and also to provide a novel means of securing 15 wall-board or other similar finish to the assembled slabs.

The present invention, therefore, has for its principal objects to provide an assemblage of novel and simply constructed building 20 units, usually made of concrete, and in the form of slabs, and a novel means of securing battens over the joints of the abutting units, when in assembled relation, as well as a novel means of attaching wall-board, or 25 other similar finish to such assembled slabs.

Other objects of the present invention not at this time more particularly enumerated, will be clearly understood from the following detailed description of the present in- 30 vention.

With the various objects of the present invention in view, the said invention consists, primarily, in the novel building unit hereinafter more fully set forth; and, the 35 said invention consists, furthermore, in the novel arrangements and combinations of the various devices and parts, all of which will be more fully described in the following specification, and then finally embodied in 40 the clauses of the claims, which are appended to the said specification, and which form an essential part of the same.

The invention is clearly illustrated in the accompanying drawings, in which:—

45 Figure 1 is an elevation of one of the faces of a wall composed of a number of building units made according to and embodying the principles of the present invention, the joints of the abutting units being shown covered by an arrangement of battens; Figure 2 is a horizontal sectional representation of the same, said section being taken on line 2—2 in said Figure 1; and Figure 3 is another elevation of the opposite 50 55 face of the wall, looking toward the as-

sembled slabs and the wall-board covering the same.

Figure 4 is a sectional representation, on an enlarged scale, of a portion of a building unit of a slightly modified construction. 60

Similar characters of reference are employed in the said above-described views, to indicate corresponding parts.

Referring now to the said Figures 1, 2 and 3 of the drawings, the reference-character 65 1 indicates, in general, an assemblage of building units, battens for closing the joints of the abutting units, and a covering of wall-board for the same, one particular means for securing the battens and the wall- 70 board in position with relation to the assembled units being represented more particularly in Figure 2 of the drawings.

From an inspection more particularly of Figures 1 and 2 of the drawings, it will be 75 seen that each unit is generally of rectangular conformation, being usually two feet in width and eight feet in length, although it will be evident that the dimensions of each unit may be varied at will, as may be de- 80 sired.

Each unit consists, essentially, of a main body-portion 2 moulded in any suitable material, usually concrete, said body being substantially smooth or flat upon one face, as at 3, and said body being provided 85 upon its opposite face with longitudinally extending re-inforcing ribs 4, and laterally extending ribs 5, said ribs 4 and 5 projecting rearwardly from the respective marginal edge-portions of the said body 2. The said 90 rear face of the body 2 may also be formed with a centrally disposed rib, as 6, which extends longitudinally of said rear face from and between the two end or laterally ex- 95 tends the ribs 5 of the slab or board thus produced. In addition to the above-men- 100 tioned ribs, the said body may also be pro- vided, intermediate the longitudinally ex- 105 tends the ribs 4 and 6, with other longitudinally extending re-inforcing ribs 7, said lat- ter ribs being preferably V-shape in cross- section.

At suitable points, the said longitudinally extending ribs 4 are provided with channels 8 of the configuration shown in Figure 2 105 of the drawings, or channels 9 of the configuration shown in Figure 4 may be em- ployed, the purpose of which will presently be more fully set forth.

To provide a wall, or similar structure, 110

two or more of the herein-above described slabs are placed side by side, that is with the longitudinally extending rib 4 of one slab placed adjacent to the longitudinally extending rib 4 of another slab, so that the channels 8 or 9 of the respective slabs are placed opposite each other, substantially as shown in Figure 2 of the drawings. In the ducts thereby provided, there is disposed a suitable filler-element 10, preferably rods or sticks of wood, which tend to lock the adjacent slabs in position, against displacement, as will be evident. The joints formed between the adjacent slabs are then closed by placing over said joints suitable strips or battens 11, of wood or other suitable material, suitable fastening or securing means 12 in the form of nails, or the like, being then driven through the said strips or battens 11, into the joints between the said adjacent slabs, and into the filler-element 10, whereby the said strips or battens 11 are securely fastened in place. If desired, wall-board 13, or other suitable finish, and an arrangement of strips or battens 14 may also be disposed against the adjacent slabs, substantially as illustrated in the several figures of the drawings, the said wall-board 13 and the battens 14 being similarly secured in place by an arrangement of nails 15, or similar fastening means, driven through the battens 14 and wall-board 13, and through the joints between the adjacent slabs into the filler-element 10, as will be clearly understood.

This arrangement and assemblage of the various parts permits suitably decorating the wall of concrete thus provided. It will also be evident that with the arrangement of the battens secured over the joints between the adjacent slabs, lath may be nailed to the battens, and a coat of plaster, or the like, may be applied over the lath.

While in the foregoing description I have described, and in the accompanying drawings, I have illustrated one construction of building unit, in the form of a slab, with an arrangement of battens secured over the joints between the assembled slabs, as well as a manner of securing wall-board or other desired finish to the said slabs, I am fully aware that other forms of concrete building units may be employed, and that various changes may be made in the general arrangements and combinations of the various

devices and parts, without departing from the scope of the present invention as set forth in the foregoing specification, and as defined in the clauses of the claims which are appended to the said specification. Hence, I do not limit my present invention to the exact arrangements and combinations of the various devices and parts as described in the said specification, nor do I confine myself to the exact details of the construction of the said parts, as illustrated in the accompanying drawings.

I claim:

1. A wall structure, comprising a plurality of perpendicular slabs disposed side by side in edge to edge relation, the faces of the edge portions of adjoining slabs each having between their sides a vertical longitudinal channel extending from the bottom to the top thereof, said channels of adjoining slabs being disposed in opposed matching relation to provide a vertical chamber intersecting the joint between the slabs, an integral filler element extending through said vertical chamber, a vertical batten covering the exterior end of the joint between the slabs, and vertically spaced fastening nails driven through said batten and the exterior end of said joint and into said filler element.

2. A wall structure, comprising a plurality of perpendicular slabs disposed side by side in edge to edge relation, the faces of the edge portions of adjoining slabs each having between their sides a vertical longitudinal channel extending from the bottom to the top thereof, said channels of adjoining slabs being disposed in opposed matching relation to provide a vertical chamber intersecting the joint between the slabs, an integral filler element extending through said vertical chamber, a vertical batten covering the exterior end of the joint between the slabs, vertically spaced fastening nails driven through said batten and the exterior end of said joint and into said filler element, an interior wall covering, and vertically spaced fastening nails driven through said wall covering and the interior end of said joint and into said filler element.

In testimony that I claim the invention set forth above I have hereunto set my hand this 7th day of September, 1922.

JOSEPH A. BIRKHOLZ.
